UNITED STATES PATENT OFFICE.

WHITMEL S. COBB, OF BIRMINGHAM, ALABAMA.

STOVE ATTACHMENT FOR GRATES.

Application filed September 3, 1918. Serial No. 252,425.

To all whom it may concern:

Be it known that I, WHITMEL S. COBB, a citizen of the United States of America, residing at Birmingham, in the county of 5 Jefferson and State of Alabama, have invented certain new and useful Improvements in Stove Attachments for Grates, of which the following is a specification.

This invention relates to an improvement 10 in a stove attachment for grates adapted to materially reduce the consumption of fuel and to increase the heating efficiency of the fuel consumed by designing the attachment to radiate the heat effectually from 15 the products of combustion before they enter the chimney flue.

It is a further object of my invention to design the attachment so that it can be inexpensively constructed and readily attached 20 without requiring skilled labor.

It is a further object of my invention to adapt the attachment to permit the ready introduction of fuel into the grate and to protect the attachment from undue wear 25 arising from the introduction of fuel.

These and the other objects of my invention will be more clearly understood by reference to the accompanying drawing which forms a part of this application, and in 30 which:—

Fig. 1 is a front perspective view of my attachment applied to a fire place.

Fig. 2 is a vertical sectional view through the fire place showing the attachment therein 35 in side elevation.

Fig. 3 is a top plan view looking down on the attachment as mounted in the grate.

Similar reference numerals refer to similar parts throughout the drawing.

40 I have shown my invention as applied to the ordinary grate 1 seated in the fire place opening 2 which has a fire brick back wall 3, an arch frame 4 and a chimney flue 5, all such parts being of any customary size 45 or shape.

My invention proper comprises a base portion 6 extending from the hearth to the top of the grate and from side to side of the fire place opening, and this base is provided with an ash door 8 having an air supply damper 9 therein. The upper or radiating portion of my grate attachment 50 consists of a curved flue formed by a front wall 10 spaced from a back wall 11 and connected thereto by similar side walls 12. The front wall 10 is disposed on an upward

and outward inclination from the top of the base member 6 and is then curved on a wide convex arc and passes substantially horizontally into the top of the fire place under the 60 top of the arch frame 4 with which it makes a snug fit. This wall 10 continues into the chimney and terminates at a damper 13 which closes the space between the adjacent 65 ends of the front and back walls 10 and 11 and permits the escape of the products of combustion from the heat radiating flue. The back wall 11 is disposed to extend from the rear upper edge of the grate with an upward and outward inclination to a point 70 beyond the fire place and is then bent about a short curve and inclined inwardly and upwardly so as to terminate adjacent to the back wall of the chimney flue at the top of the fire place. As seen in Fig. 3, the top 75 portions of the walls 10 and 11, where they project into the fire place, are inwardly tapered and the side walls are sloped inwardly so as to contract the discharge opening 14 for the products of combustion which is 80 controlled by the damper 13. This damper 13 is operated by a rod 15 connected at one end to a suitable crank arm 17 mounted to turn at an exposed position in one of the side walls 12. These side walls are provided with straight continuous vertical side flanges 18 extending from the base 6 to the 85 top of the arch frame and overlapping the sides of the arch frame. These flanges are adapted to be made secure to the arch frame 90 by means of Z-shaped clips 19 which catch behind the inner faces of the sides of the arch frame and are connected to the flanges 18 by bolts or screws 20. By this arrangement I avoid the necessity for drilling the 95 arch frame to mount the attachment in the fire place.

The front curved wall 10 carries in its upper portion a fuel door 21 which opens outwardly and the lower portion of this 100 wall 10, upon which the fuel would fall, is reinforced by a cast metal wear plate 22. I also preferably interpose a cast metal plate 23 in the top of the wall 10 between the door and the arch frame and adjacent to the arch frame. I provide this inside plate with a downturned baffle 24, which tends to restrict the outflow of the products of combustion towards the opening 14 and reduces the temperature of the front wall 10 adjacent to 110 and behind the arch frame.

It is preferable that the bottom portions

of the walls 10 and 11, where they project into the fire place above the grate, should be contracted like their top portions and the lower end of the side walls 12 beyond the flanges 18 should therefore be bent inwardly. With such an arrangement it is essential that the grate should be filled at each side with suitable material so as to restrict the fuel receiving space on the grate to the size 10 of the bottom end of the radiating flue.

In operation, having assembled the attachment in the manner described, a fire is lighted in the restricted grate, the air damper 9 is adjusted to admit the requisite 15 amount of air to maintain combustion, and the heated products flow upwardly through the radiating flue, serving to heat the side and front walls equally so that their maximum heating efficiency is extracted and their 20 flow retarded by the baffle 24 and damper 13. The rate of consumption of the fuel is controllable by the dampers 13 and 9. As the fuel is consumed additional fuel is introduced through the door 21 and falls 25 upon the plate 22 and thence is deflected into the grate.

In practice, I have reduced the fuel consumption in grates to half of the normal consumption and obtained a greatly increased amount of heat therefrom.

This invention is not intended to be restricted in scope to the specific embodiments shown, but contemplates such modifications as come within the spirit and scope of the 35 claims.

Having thus described my invention, what I claim as new and desire to secure by Letters Patent, is:—

1. The combination with a normal fire-place having a grate and chimney flue, of 40 a stove attachment comprising spaced inner and outer walls connected by sides to form a detachable curved radiating flue, means to set said stove attachment in the fire-place with its bottom open end resting 45 on and covering the whole fuel supporting surface of the grate and with its main curved body portion projecting substantially without the fire-place, means to control the 50 admission of air to the grate below the intake end of said flue, a door in said flue for

the admission of fuel to the grate, and a damper in said flue for controlling the flow of products therethrough, substantially as described.

2. In a grate attachment, spaced inner and outer walls having sides to form a curved radiating flue, means to mount said parts with the lower end of the flue covering the grate and with the upper end of the flue 60 entering the chimney, a base plate with a damper therein controlling the admission of air to the grate below said flue, outwardly flanges on said sides adapted to engage the arch frame about the fire place, and 65 clamp means to detachably connect said flanges to the frame.

3. A grate attachment having a radiating flue therein formed by inner and outer curved walls having side walls connecting 70 them in spaced relation, said attachment being adapted to fit into and close the fire place opening above the grate and to have the lower inner end of the flue project into the fire place, said lower inner end of the 75 radiating flue being contracted in width, means to control the admission of air below the grate, and means to close in the sides of the grate to the sides of the said bottom end of said radiating flue.

4. In a fire place attachment, means enclosing the fire place opening and comprising a convex flue projecting outside of the fire place opening, a fuel door in the upper portion of said flue, and means to reinforce 85 the lower inside portion of the flue upon which the fuel will fall before entering the fire place, substantially as described.

5. In a fire place attachment, means enclosing the fire place opening and comprising a convex radiating flue projecting outwardly of the fire place opening, a bottom air inlet damper in said attachment, a fuel door in the upper portion of said flue, and a downturned baffle disposed in the upper portion of said flue between the top of the door and the fire place opening, as and for the purposes described.

In testimony whereof I affix my signature.
WHITMEL S. COBB.
